149,520

DESIGN FOR A FLEXIBLE POCKET BILL-FOLD OR SIMILAR ARTICLE

Robert H. Rolfs, West Bend, Wis., assignor to Amity Leather Products Co., West Bend, Wis.,
a corporation of Wisconsin

Application April 18, 1947, Serial No. 138,484

Term of patent 14 years

(Cl. D87—3)

To all whom it may concern:

Be it known that I, Robert H. Rolfs, a citizen of the United States, residing at West Bend, in the County of Washington and State of Wisconsin, have invented a new, original, and ornamental Design for a Flexible Pocket Billfold or Similar Article, of which the following is a specification, reference being had to the accompanying drawing, forming a part thereof, in which

The design is characterized by the plate or strip attached to the billfold at one end thereof substantially as shown in the accompanying drawing. The essential features of my new design reside in the portions shown in full lines.

The present application is filed as a continuation in part of my application for design patent for Flexible pocket billfold, filed June 28, 1946, Serial No. D. 131,116, now abandoned.

I claim:

The ornamental design for a flexible pocket billfold or similar article, substantially as shown and described.

ROBERT H. ROLFS.
